UNITED STATES PATENT OFFICE.

MORRIS KEIL, OF NEW ORLEANS, LOUISIANA.

SEPARABLE FASTENER.

Application filed May 3, 1922. Serial No. 558,083.

To all whom it may concern:

Be it known that I, MORRIS KEIL, a citizen of the United States, residing at New Orleans, in the parish of Orleans and State 5 of Louisiana, have invented certain new and useful Improvements in Separable Fasteners, of which the following is a specification.

The invention relates to separable fasteners, and has as an object the provision of 10 a fastener having separable elements, one of which may be secured to one object and the other element to a second object to be fastened to the first wherein the longitudinal relation of the objects is liable to differ.

15 A further object of the invention is the provision of a separable fastener one element of which is freely slideable so as to be readily brought opposite the other element when the longitudinal relation of the parts 20 to be fastened together differs.

Illustrative embodiments of the invention are shown in the accompanying drawings, in which

Fig. 1 is a front view;

25 Fig. 2 is a rear view;

Fig. 3 is a side elevation partly in central vertical section at right angles to the view of Fig. 1;

30 Fig. 4 is a perspective view of a modification showing portions of objects to be fastened together in dotted lines.

In Figs. 1 to 3 inclusive, as shown, the device comprises a vertical rigid rod 10 carrying one element 11 of an ordinary 35 glove fastener type of separable fastener. To secure the element 11 to the rod 10 so as to be readily slideable thereon loops 12, as shown, are secured to the element 11 and enclose the rod 10. The loops 12 may be secured to the element 11 in any desirable 40 manner as by soldering or as by being passed through perforations therein and being headed down on the opposite side.

The second element of the separable fastener comprises the disk 13 carrying springs 45 14 which are adapted to snap under the head 15 of the element 11. A cap 16 is formed by striking up the metal of the disk 13 and slots are provided in the sides thereof for reception of the springs 14. No novelty is claimed for the form of fastener per se.

To secure the rod 10 to one of the objects 50 to be fastened together eyes 17 are shown 55 formed upon its ends, which eyes may be sewn to the object. The disk 13 may be

secured to the other object to be fastened to the first, as by sewing, in accordance with the usual practice.

The device may be used in fastening the 60 two portions of a four-in-hand necktie, so that they will not blow in different directions when worn without a vest, thus avoiding a very annoying habit of such ties without the use of a stick pin, which is ordinarily utilized for the purpose. The two 65 elements of the device are adapted to be permanently sewn to the portions of the tie, and even though the tie is not made up with its ends in exact register yet the fastener 70 may be snapped together by sliding the element 11 upon the rod 10 to the necessary location opposite the fixed element 13.

It is important that the rod 10 shall be 75 rigid as distinguished from a flexible element, such as a thread or chain, since a device of the latter nature would bow out at the center and fail to hold the two portions of the tie in closely adjacent relation.

A modification of the invention is shown 80 in Fig. 4, in which the rod 10 is fastened to one portion, as 18' of an object such as a tie, and in which the fixed portion of the fastener comprises a snap hook 19 which may be fastened to the rear of the other portion 85 18' of the tie. The action of this form of the device is in all respects similar to that of the first described and preferred modification of the device.

In Fig. 1 there is indicated at 18 a portion 90 of an object to which the rod 10 is shown as secured.

Minor changes may be made in the physical embodiment of the invention without departing from its spirit.

I claim:

1. A separable apparel fastener comprising, in combination, an elongated element, means on said element whereby it may be secured to a fabric, a fastener comprising 100 two members, readily separable means for securing said members together, means on one of said members embracing said element to slidably mount said member thereon, the second member adapted to be fixedly 105 secured to fabric to be secured to said first named fabric.

2. A separable apparel fastener comprising, in combination, an elongated element adapted to be sewn to fabric, a snap fastener 110 comprising two members, one of said members slidably secured to said element, the

second member adapted to be sewn to a portion of fabric to be secured to said first named fabric.

3. A separable apparel fastener comprising, in combination, an elongated element adapted to be sewn at its ends to a fabric, a snap button comprising separable disks, loops projecting from the rear of one of said disks and slidably embracing said element, the other of said disks adapted to be sewn to a fabric to be attached to said first named fabric.

4. A separable apparel fastener comprising, in combination, a member adapted for fixed location on a fabric, a slidable member adapted for separable connection with said first named member, and means adapted to be secured to a second portion of fabric and on which said last named member is slidably mounted, whereby said slidable member may be adjusted to connect with its coacting fixed member in varying positions of the latter. 15 20

MORRIS KEIL.
